UNITED STATES PATENT OFFICE.

BENJAMIN H. DE HAVEN, OF PITTSBURGH, PENNSYLVANIA.

SHAVING-BRUSH.

1,382,347.

Specification of Letters Patent. Patented June 21, 1921.

Application filed December 29, 1919. Serial No. 348,064.

To all whom it may concern:

Be it known that I, BENJAMIN H. DE HAVEN, a citizen of the United States, residing at Pittsburgh, in the county of Allegheny and State of Pennsylvania, have invented certain new and useful Improvements in Shaving-Brushes, of which the following is a specification.

This invention relates to a fountain brush and more particularly to a shaving brush and has for its principal object the provision of means whereby liquid soap or water may be carried in the handle of the brush for moistening the brush when so desired by the user.

Another object of this invention is the provision of means whereby the liquid may be applied to the brush proper in small quantities as may be desired by the user.

With these and other objects in view, this invention consists of certain novel combinations, constructions and arrangement of parts as will be hereinafter more fully described.

In the accompanying drawings:—

Figure 1 is a vertical section taken through my invention.

Fig. 2 is an enlarged detail vertical section taken through my invention showing the valve mechanism in detail.

Fig. 3 is a section taken on the line 3—3 of Fig. 2 looking in the direction of the arrow, and

Fig. 4 is a section taken on the line 4—4 of Fig. 2 looking in the direction of the arrow.

By referring to the accompanying drawing by numerals it will be understood that 1 designates the liquid container which also 40 acts as a handle for the brush. This container 1 is cylindrical shaped and hollow so as to contain either water or liquid soap as may be desired. Threadedly mounted upon the top portion of the tank 1 is provided the 45 cover 2 for filling the tank as may be desired. This cover 2 is provided with the depending cylindrical portion 3 for receiving the coiled springs 6. It will be seen that the depending portion 3 is bent inwardly so 50 as to engage the bottom of the coil spring 6. A barrel 4 is situated upon the cover 2 so as to register with the depending cylindrical portion 3 and receive the upper portion of the coil spring 6. The rod 5 extends 55 through the coil spring 4 and has provided at its top end the knob 7 and

adjacent the bottom portion of the depending portion 3 there is situated the stop 8. A casing 6 is provided around the knob 7 and extends a short distance into the depending portion 3 thereby protecting the coil spring which is extended above the cover 2. The rod 5 extends longitudinally with the tank 1 and is provided with the bifurcated end portion 9 to which is integrally 60 connected the collar 10 having a central opening. Hingedly mounted to the bottom of the collar 10 is provided the valve 14 which is normally held in a closed position by means of the spring 17 shown to advantage in Fig. 4.

In the center of the body 11 of the tank 1 there is provided the depending cylinder 12 which has the bottom 13 provided with a central opening and the hingedly mounted 75 valve 15 which is also normally held in a closed position by means of a spring similar to the spring 17 shown in Fig. 4. The bristles 16 of the brush are held in any suitable manner between the lower walls of the 80 tank 1 and the cylinder 12 as is clearly shown in Fig. 1 of the drawing. It will be seen that these bristles will completely surround the cylindrical portion 12 so that when liquid flows therefrom it will readily saturate 85 the lower portions of the bristles 16.

When the tank 1 is filled with the desired liquid it will be seen that by pressing downwardly upon the rod 5 what liquid is in the cylinder 12 will be forced through the opening provided in the bottom 13 because of the pressure against the valve 15. When all the liquid is displaced from the cylinder 12 it will be seen that the spring 17 will close the valve 15 and the spring will raise the rod 90 5 thereby causing the weight of the liquid contained in the cylinder 1 to be upon the valve 14. The spring 17 is of a tension which will allow the weight of the liquid to open the valve so as to allow the same 95 to flow into the cylinder 12 when the pressure is equalized by the cylinder 12 becoming filled and it will be seen that the spring 17 will then have sufficient tension to close the valve 14. When the valve 14 is closed 100 the rod 5 may be pressed downwardly and the liquid contained in the cylinder 12 may be dispelled therefrom as described above.

From the above description it is thought that a clear understanding of this invention 110 will be had and that the use of the same will be clearly understood. Of course, either

liquid soap may be placed in the container 1 or water as the user may desire and a small amount of this liquid may be applied to the bristles as desired by the user. The 5 above drawing and description refer to what I may call the preferred form of my invention and I wish it understood that I may make such changes in arrangements, constructions, and combinations as fall with- 10 in the scope of the appended claim.

Having thus described my invention, what I claim as new is:—

A device of the class described including a tank, a rod extending longitudinally of 15 said tank, and provided with a bifurcated end portion, a collar integrally mounted upon said bifurcated end portion, a valve

hingedly connected to said collar, said tank being provided with a bottom, a cylinder extending from said bottom running parallel with said tank, said collar provided upon said rod being adapted to slide within said cylinder, a partition provided in said cylinder, said partition having an opening, a valve hingedly mounted in said partition, and 20 springs provided for normally holding said valves in a closed position.

In testimony whereof I affix my signature in presence of two witnesses.

BENJAMIN H. DE HAVEN.
